CART FOR TRANSPORTING A GOLF BAG OR THE LIKE

Joseph Henry Gunning, Los Angeles, Calif.

Application December 26, 1950, Serial No. 13,593

Term of patent 14 years

(Cl. D14—3)

To all whom it may concern:

Be it known that I, Joseph Henry Gunning, a citizen of the United States, residing at Los Angeles, county of Los Angeles, State of California, have invented a new, original, and ornamental Design for a Cart for Transporting a Golf Bag or the like, of which the following is a specification, reference being had to the accompanying drawing, constituting a part thereof:

Fig. 1 is a perspective view from the front quarter of a cart for transporting a golf bag or the like, showing my new design;

Fig. 2 is a front elevation of the cart of Fig. 1;

Fig. 3 is a side elevation of the cart of Fig. 1; and

Fig. 4 is a plan view of the cart of Fig. 1.

The golf bag is shown in dotted lines for illustrative purposes only.

I claim:

The ornamental design for a cart for transporting a golf bag or the like, substantially as shown and described.

J. HENRY GUNNING.
